METAL FALSEWORK CARRIER FOR REINFORCED BRICKWORK AND REINFORCED CONCRETE STRUCTURES

Otto Hinze, Hannover-Kleefeld, Germany, assignor to Johann Friedrich Zwicky, Zurich, Switzerland

Application August 18, 1950, Serial No. 180,186

8 Claims. (Cl. 189—37)

1

Floors and roofs, as well as other structural parts of dwelling houses and industrial buildings are now frequently built up of prefabricated concrete units. This system affords the following advantages:

The prefabricated units can be prepared indoors independently of the exterior weather conditions. Fewer skilled workers are necessary for their preparation and erection than is the case with other methods of building, and they save the large quantity of falsework and scaffolding timber otherwise consumed during building operations. On the other hand, however, it is not possible when building with prefabricated units to make full use of the homogeneous cohesion, resistant to bending and shear, that characterizes monolithic-cast concrete. The clamping fixation otherwise preferentially employed has to be dispensed with. In consequence, prefabricated units are less suitable for buildings of appreciable height, such as multi-story houses. Moreover, the great weight of the prefabricated units for conveying, lifting and shifting calls for correspondingly powerful lifting and conveying tackle. Furthermore, a structure built up of prefabricated units must be so designed that subsequent supplementary loads are excluded. Caulking work may not be performed. And pipe-work can be subsequently secured only by straps or pipe clips placed round stanchions and girders. It is accordingly not always possible to dispense with monolithic building methods in the case of floors in structures subjected to heavy stresses, as for instance in multi-story dwelling houses, factory bays, and buildings which are constantly exposed to considerable vibration from machines.

Ceilings, roofs and vaults of brick, reinforced brickwork or reinforced concrete are produced monolithically by means of negative moulds, known as shuttering, casing, falsework or centering. These moulds need remain in position only for a relatively short time, and they are therefore not expected to exhibit very long life. The casing or falsework is generally made of timber with its concrete side left rough, more or less carefully finished, or even lined with sheet steel. The boards or panels are placed on squared timbers which are arranged with a spacing of 70 to 80 cm. between each two and supported by bearers consisting of squared timber. The bearers are carried by vertical props, usually round timbers, which are set up on planks and wedges at intervals of 0.80 to 1.10 metres according to the anticipated loading. With an eye to buckling resistance, close spacing of the slender stanchions subjected to compressive stress

is absolutely necessary. The props are, moreover, strengthened horizontally and vertically by poling boards or battens, for horizontal stresses may arise even when, according to plan, only vertical loading was anticipated. Conventional timbered floor or ceiling falsework structures have therefore a veritable maze of vertical supporting members. No work can be successfully performed in a room in which such falsework is erected; it is even difficult to pick one's way through the resultant confusion of props and poling boards. According to the type of cement used and to the greater or lesser stressing the time which must elapse before the falsework is removed may range from 2 to 21 days, and the so-called emergency props remain in position 14 days longer. The obstructive effect of wooden falsework is therefore a substantial drawback. Furthermore, the high consumption of timber is at present no longer justifiable from the point of view of national economy. Finally, timber falsework calls for a comparatively heavy expenditure of working time for fitting and removal.

Efforts have long been made, therefore, to replace timber floor-falsework by metal falsework. Thus, for instance, trussed beams and truss-frames have been designed which are assembled from a plurality of separate units. These supporting systems have a considerable structural height, their component units are relatively heavy and unwieldy and in consequence inconvenient. For these reasons it can doubtless be claimed that even today timber falsework is still preferred. A low structural height is not suitable in the case of the falsework carriers hitherto known built up of a plurality of component elements, as it leads to sagging as a result of the absence of vertical props. Needless to say, the ceiling would likewise sag if cast on such a sagging falsework; the sag would be aggravated by the effect of the superload. For this reason, falsework carriers have hitherto been made very high. The result of this has been comparatively heavy structural elements which, when assembled, are obstructive.

The object of the invention is to provide camberable metal falsework carriers built up of light and convenient structural elements which are easily assembled and dismantled, camberable to offset the sagging that is inevitable under load, and in addition have sufficiently lateral rigidity to absorb any horizontal stresses that may arise during the erection of the ceiling or floor. Furthermore, their use is intended to be less expensive than that of the timber falsework hitherto

2

55

3

usual, and they are adapted to give the ceiling as smooth as possible an undersurface.

According to the invention this problem is solved by short, low and light-weight carrier elements or sections butt-jointed at the top member and connected at the bottom member by coupling nuts, said carrier sections taking the form of a parallel trussed frame and being arranged for assembly into homogeneously-acting, space-spanning metal falsework carriers or girders.

The several sections of carrier are advantageously made of such length that they can be fitted into a standard system of dimension units. In this way, for instance, using only carrier sections in the serial lengths of 0.625 m., 0.9375 m. and 1.25 m. all spans of 1.25 m. upwards dimensioned in accordance with the standard dimension unit of

$$0.3125 \left(= \frac{1.25}{4} \right)$$

can be spanned. Or by means of serial lengths of 0.50, 0.60 and 0.70 metres, all spans of 1 metre upwards, rising by intervals of 0.10 metre, could be accommodated.

The carrier sections designed in the form of a parallel trussed frame enable material to be economized and a structure of the lowest possible weight to be achieved.

The drawing shows by way of illustration satisfactory examples of the construction of falsework carriers in accordance with the invention. In said drawing,

Fig. 1 shows an elevation of an erected falsework carrier consisting of two lateral and two central truss elements, with the ceiling produced with its aid in section;

Fig. 2 shows in transverse section erected falsework carriers in the form of the so-called band falsework for ribbed ceilings made from reinforced stone or reinforced concrete;

Fig. 3 shows schematically in elevation a falsework carrier consisting of two truss elements;

Fig. 4 is an enlarged end view;

Fig. 5 is a front view of an element of the falsework carrier;

Fig. 6 shows a cross-section through an element of a construction slightly differing from Figs. 4 and 5;

Fig. 7 is a front view of an element arranged at a side wall;

Fig. 8 is a side view of the lateral suspension support of a truss element according to Fig. 7;

Fig. 9 is a side view of the upper chord member or beam of the truss element and a turnbuckle linking two elements together in end-to-end relationship at their lower chord member or beam, and being always adjustable and linked to the elements at both sides and separately;

Fig. 10 is a plan view of the turnbuckle according to Fig. 9; while

Fig. 11 shows the eye screws of the turnbuckle according to Fig. 10.

As will be seen from Figs. 1, 4, 5, 7, 8 and 9, the metal falsework carrier of the present invention freely spans the space to be bridged, and is camberable and detachable as is evident from Figs. 1 and 9. It consists of at least two structural elements or trusses, each consisting of at least an upper chord or beam 3 (Fig. 4), a lower chord 4 and the rods 5, two neighboring elements 1 and 2, 2 and 2, and 2 and 1 being in end-to-end relationship in the line of the upper chord 3. The elements are safeguarded against shifting in

4

relation to each other in the plane of abutment (Fig. 9) and in the line of their lower chords 4 by means of connecting elements which are illustrated in the embodiment of the invention 5 shown as being in the form of turnbuckles 8 (Figs. 9 to 11) which are adjustable lengthwise and are linked to elements 1, 2, or 2 and 2, or 2 and 1, to one side and separately. It is immaterial whether a wall-adjacent or anchoring 10 element 1 links up with a central element 2, as in Fig. 1; or whether, according to such figure, an intermediate element 2 links up with a second intermediate element 2; or an intermediate element 2 links up with a wall-adjacent element 1; or a wall-adjacent anchoring element links up with a number of intermediate elements as in Fig. 3.

The upper chords 3 are made from U-shaped profile sheet metal; this may be replaced by any 20 other suitable, preferably commercial profiles (for small spans and loads also light profiles). The lower chords 4 preferably consist of round steel rods or tubes. It is possible to use also built-up sections as shown in Fig. 6. The upper 25 and lower chords are connected by one or two series of round steel rods or pipes 5, preferably welded to the chords 1 and forming the struts of the latticework; the illustrated connection may be replaced by any other suitable latticework or 30 paneling between the upper and the lower chords as conditions may require, and even a continuous web. The upper chords are so shaped at their ends that they may be abutted flatly along a wide area; in addition, they can be held together 35 at their abutting faces by means of screw bolts or by slip-on locks or clamps 9, as shown for instance in Fig. 9.

The locking devices for the upper chord 3, such as screw bolts or slip-on locks or clamps, 40 are particularly suitable for the mounting of the falsework carrier, as they prevent the elements from gapping. At the same time, the linking of the upper chords serves to take up any transverse and horizontal stresses which may occur in the 45 course of the construction of ceilings. In order to make possible an easy removal of the falsework, the locking devices of the upper chord are advantageously arranged in such a manner that after the setting of the ceiling they are not 50 exposed to any stresses worth mentioning.

With the help of the turnbuckles, the falsework carrier is aligned in the line of the lower chords 1, and the desired arching is gauged. When removing the falsework, the turnbuckles 55 serve as releasing devices; the falsework carrier, being under tension, is easily detached.

The permanent structural parts for the support of the ceiling are used as the hangers for the falsework carriers, as shown in Figs. 1 and 3. 60 For this purpose the wall-adjacent supporting elements 1 are provided with tongue-like projections 18 which are rigidly connected with such parts. Figs. 7 and 8 show such an end piece with tongue 18 in front and side views. Mov- 65 able supports or brackets fixed to the wall may also be used to support the falsework carriers. Struts 17 which are wide in relation to their height can be provided to inter-connect several adjoining falsework carriers and thus increase 70 their lateral rigidity. Fig. 2 shows at 15 the arrangement of transverse rods for increasing the lateral rigidity of the entire unit consisting of a number of falsework carriers; in their stead, or in addition, diagonal rods may be provided, 75 which may connect for instance the first false-

work carrier element to the left with the last element to the right.

Falsework carriers made in accordance with the invention have the particular advantage of high load capacity combined with light weight and easy handling. Thus with a falsework carrier according to the invention for use in the building of apartments, a weight of 12 kg./meter at an assumed span of 6 meters leads to a bending moment such that the weights of the concrete usually used for the construction of ceilings as well as of the traffic and of the receptacles for the concrete may be taken up, with the prescribed factors of safety.

The above-described construction results in a considerable advance in building technique, which is characterized by the figures of 0.15 to 0.30 h./m² for the erection and detachment including the connecting together and taking apart of the falsework carrier. Owing to the simple and constantly variable adjustment of the turnbuckles, the exact gauging of the camber or arching presents not the slightest difficulty, so that completely flat ceilings can be realized. In addition to the advantage of the accessibility of the spanned spaces, further advantages arise from the fact that through the elimination of stiffening supports the possibility of their sinking on undependable floors is avoided, as well as premature and undesired stress on the ceilings below. An almost unlimited life of the falsework is ensured as against the use of timber which is perishable and may easily be stolen, by the possibility of using high-grade materials in the construction of the falsework, by safeguarding against rust, by doing away with loose parts and thus making loss thereof impossible, and by the practically non-existing wear and tear. In so far as metal falsework carriers have already been proposed, they have, owing to their telescopic structure, to their construction of varying static systems on the pattern of bridges, or through their remaining in the building structure as reinforcements, a much greater weight, and are unwieldy, mostly non-camberable or capable of being arched, and for these and other reasons have not been introduced to any considerable extent in the practical building technique.

I claim:

1. A light-weight structurally self-contained sectional lattice beam structure, suited to engage supports at its ends and to be loaded between said supports, comprising: a top member composed of at least two sections which abut end to end in their load bearing position to react horizontally against one another directly in thrust; releasable means joining adjacent sections of the top member; a bottom member composed of a like number of sections which are aligned and react in tension, said top and bottom members being of substantially the same length; means connecting the top and bottom members of each section together in spaced relation; and tension connecting means joining the sections of the bottom member, the tension connecting means between at least one pair of adjacent sections being positively adjustable in length; whereby an upward camber may be produced in the upper surface of the structure such that deflection produced by the ultimate superimposed working load will substantially neutralize said camber.

2. A detachable sectional carrier for use in building construction comprising: a plurality of sections; each of said sections including an upper

chord and a lower chord spaced therefrom; means interconnecting said upper and lower chords; each two neighboring sections including transverse surfaces at the ends of the upper chords to abut for transmission of compressive stresses under superimposed loads; releasable means joining said sections at their upper chords; and positive means infinitely adjustable between predetermined limits interconnecting neighboring sections adjacent said lower chords; whereby an upward camber may be produced in the upper surface of the carrier such that deflection produced by the ultimate superimposed working load will substantially neutralize said camber.

3. A detachable sectional carrier for use in building construction comprising: a plurality of sections; each forming a unitary constructional part and including an upper chord and a lower chord spaced therefrom, each such section further including means interconnecting said upper and lower chords, and transverse surfaces at the ends of the upper chord forming abutments for transmission of compressive stresses under superimposed loads; releasable means joining said sections at their upper chords; and positive adjustable means including connections between the sections adjacent said lower chords, at least one of said connections being flexible; whereby an upward camber may be produced in the upper surface of the carrier such that deflection produced by the ultimate superimposed working load will substantially neutralize said camber.

4. A detachable sectional carrier for concrete forms and the like comprising: at least two sections each including an upper chord and a lower chord and elements interconnecting these two chords; each two neighboring sections further including transverse surfaces at the ends of their upper chords providing thrust bearings for transmission of compressive stresses in a direct line between the neighboring sections when under load with said transverse surfaces in contact with one another; releasable means positively joining adjacent sections at said transverse surfaces; and turnbuckles interconnecting neighboring sections adjacent said lower chords; whereby a positive camber may be produced in the upper surface of the carrier such that deflection produced by the ultimate superimposed working load will substantially neutralize said camber.

5. A detachable sectional carrier for concrete forms and the like comprising: a plurality of sections each forming a unitary constructional part and including an upper chord, a lower chord, and interconnecting elements, each such section further including transverse surfaces at opposite ends of its upper chord providing thrust bearings for transmission of compressive stresses when the carrier is under load; releasable means positively joining said sections at their upper chords; and flexible means including turnbuckles interconnecting the sections adjacent said lower chords; whereby a positive camber may be produced in the upper surface of the carrier such that deflection produced by the ultimate superimposed working load will substantially neutralize said camber.

6. A carrier as defined by claim 5 in which the upper chords of the several sections of the truss are formed of flat plate-like elements which include downwardly extending marginal flanges and in which the marginal flanges at the ends of the sections provide said transverse thrust bearing surfaces.

7. A detachable sectional carrier for concrete forms and the like comprising: a plurality of sections of varying length for selective assembly to provide a plurality of combinations to vary the overall length of the carrier, each such section forming a unitary constructional part and including an upper chord, a lower chord, and interconnecting elements, each such section further including transverse surfaces at opposite ends of its upper chord providing thrust bearings for transmission of compressive stresses when the carrier is under load; releasable means joining said sections at their upper chords; and flexible means including turnbuckles interconnecting the sections adjacent said lower chords; whereby an upward camber may be produced in the upper surface of the carrier such that deflection produced by the ultimate superimposed working load will substantially neutralize said camber.

8. In a detachable sectional falsework carrier for use in building construction, a section comprising: an upper compressive chord member having substantially greater transverse width than depth; a lower tension chord member; means joining said members in fixed spaced relation; means substantially co-extensive in width with and positioned at each of the ends of the

upper chord member affording a releasable butt connection for transmission of compression loads between similar adjoining sections; and means positioned at each of the ends of the lower chord member affording, when connected to a similar section, a joint positively adjustable longitudinally of the section; whereby two or more of said sections may be joined to provide a false-work carrier which may be cambered upwardly so that deflection produced by the ultimate superimposed working load will substantially neutralize said camber.
